Oscar A. De Long, Inventor
By his Attorney, Fred Parker

UNITED STATES PATENT OFFICE.

OSCAR A. DE LONG, OF GLEN RIDGE, NEW JERSEY.

SAFETY-PIN.

SPECIFICATION forming part of Letters Patent No. 640,542, dated January 2, 1900.

Application filed April 19, 1899. Serial No. 713,569. (No model.)

To all whom it may concern:

Be it known that I, OSCAR A. DE LONG, a citizen of the United States, residing at Glen Ridge, in the county of Essex and State of New Jersey, have invented new and useful Improvements in Safety-Pins, of which the following is a specification.

This invention relates to that class of safety-pins known as the "shielded" variety, wherein a guard or shield is provided for the pin-point when closed; and the object of my improvement is to enable safety-pins of this type to be more conveniently handled, both in opening and closing them, as well as to provide a locking means to prevent the pin from being accidentally opened.

In the drawings accompanying this application, Figure 1 is a plan view of my improved safety-pin in the closed position. Fig. 2 is a cross-sectional view, enlarged, taken on the line 2-2 of Fig. 1. Fig. 3 is a similar view to that shown in Fig. 2, but embodying another form of my modification.

As is well known, many improvements have been introduced in safety-pins in recent years, and the guard or shield that is employed in various forms performs a very useful function by covering the pin-point when closed, and thereby preventing its catching in the flesh of the unwary user; but I do not find that any satisfactory method has been hitherto made known to prevent the pin from becoming unfastened, excepting, of course, its spring tension derived from the usual coil. To remedy this deficiency, I have invented, in conjunction with a shield, a doubled guide-strip whose contiguous leaves each have a registering corrugation united to form a bulb. Said bulb, being located midway between the two walls of the shield and the space between each wall and the bulb being insufficient to permit the passage of the pin therebetween without tensional enlargement thereof, it will be seen that a frictional and tensional lock is thus produced.

A indicates the shank of a safety-pin, B the tongue united therewith by coil C, and D indicates a guard or shield for the pointed end of the tongue. The shield D consists of a doubled strip of metal, which at a incloses the end of shank A and is clamped thereover, the two ends of the metal at this point being con-

tinued to form a guide-strip E, both of said ends having an outward corrugation a' a^2 in a plane parallel with shank A, said two corrugations coinciding and together constituting a bulbous formation, as seen. The folded strip of metal forming the shield D is curved from the point where it connects upon the end of shank A, and it terminates in an open portion F, which lies in a plane approximately parallel with shank A. Said portion F forms the socket for tongue B, and its walls or ears f' extend at the sides of and inclose the bulb a' a^2 , leaving a space between the latter and each wall somewhat less than the bulk of the tongue B that passes therethrough.

As seen in Fig. 3, the wall f is corrugated coincidentally with corrugation a' and the wall f' with corrugation a^2 , a curved passage-way being thereby formed at each side of the guide-strip E, said passage-ways being throughout their extent somewhat narrower than the bulk or cross-section of the tongue B, so that said tongue when passed into its socket must traverse either one of said passage-ways under and against friction and tension and be returned in like manner. By this means the accidental unlocking of the pin is rendered well-nigh impossible.

The two members of guide-strip E meet at their free ends and preferably continue from the corrugations a' a^2 in pear form to present at their tips a rounded inclined surface that will permit the tongue B to slip thereover easily when pressed inwardly for the purpose of release. Likewise the opposite sides of corrugations a' a^2 are properly curved and not too abruptly rounded, so that the tongue B when being passed into its socket, may not catch solidly against the side of the bulb, but will slip thereover readily to enter the frictional tensional passage-way.

The edges of the walls or ears f' where met by the tongue B in closing may be slightly flared outwardly, as indicated in Figs. 2 and 3, the better to permit said tongue to find its entrance.

Having now described my invention, I declare that what I claim is—

1. In a safety-pin having a shank and tongue, a shield comprising a socket and a guide-strip integral therewith, whose contiguous leaves each have a registering cor-

rugation united to form a bulb and extended part way into said socket; leaving a space on each side of said bulb insufficient to permit the passage of the pin, without tensional enlargement thereof, substantially as set forth.

2. In a safety-pin, in combination, a shank and tongue and a shield secured to the former and forming a socket for the latter, said shield, where connected to the shank, consisting of a doubled guide-strip, corrugated in bulb form, and the socket portion of said shield having walls extending over said

guide-strip with intervals therebetween, said walls being coincidentally corrugated with said guide-strip, to provide curved passages therebetween. 15

In testimony whereof I have hereunto set my hand in the presence of two subscribing witnesses.

OSCAR A. DE LONG.
